INKING MECHANISM

Filed Jan. 14, 1926

UNITED STATES PATENT OFFICE.

JOHN J. HALLIWELL, OF TUCKAHOE, NEW YORK, ASSIGNOR TO R. HOE & CO., INC., OF NEW YORK, N. Y., A CORPORATION OF NEW YORK.

INKING MECHANISM.

Application filed January 14, 1926. Serial No. 81,197.

This invention relates to certain improvements in inking mechanism for printing machines.

In certain types of inking mechanism, particularly that shown in United States Letters Patent No. 1,214,856, dated February 6, 1917 and No. 1,311,198, dated July 29, 1919 to B. C. White, the ink is delivered or supplied through a series of independent conduits a 10 separate conduit being provided for each column or other desired section of the form. In this type of inking mechanism the ink is delivered under pressure to the conduits in regulated quantity by a plurality of pressure 15 devices such as pumps, one pump being provided for each conduit, and the conduits deliver to separate nozzles which are arranged to extend across the mechanism adjacent the member to which the ink is to be delivered, 20 these nozzles or openings being provided in a frame or frame member which, in this type of mechanism, is termed the ink rail.

The nozzles or openings are provided one for each column or section of the form. Under some circumstances it becomes desirable to produce products having different numbers of columns or other form sections, and where it is desired to produce a product having a different number of columns or form sections 30 from that for which the distributing nozzles or openings are designed, it is necessary to dismantle the ink rail and conduits and substitute a rail having a different arrangement or number of distributing openings. 35 This operation is slow and takes up an amount of time which, in press operation, is undesirable because of the necessity of quick adjustments.

It is the especial object of the present invention to produce a construction in which the ink distributing openings or nozzles can be readily and quickly varied to accommodate the mechanism to products having varying numbers of columns or form sections.

It is a further object of the invention to produce such a construction which is simple, easily accessible and in which the parts can be quickly and accurately adjusted.

With these and other objects not specifically referred to in view, the invention consists in certain novel parts, arrangements and combinations which will be described in connec-

tion with the accompanying drawings and the novel features pointed out in the claims hereunto annexed.

55

Referring now to these drawings—

Figure 1 is a sectional side view of the improved inking mechanism partly broken away, showing the ink rail and part of a distributing cylinder, the section being taken on the line 1—1 of Figure 6.

Figure 2 is a plan view, with cover removed, showing the improved ink distributing member.

Figure 3 is a detail plan view on a much enlarged scale of part of the improved ink distributing member.

Figure 4 is a front elevation of the construction shown in Figure 3.

Figure 5 is a side view of part of the construction shown in Figure 1, looking in the direction of arrow 5 of that figure.

Figure 6 is a sectional side view of part of the construction shown in Figure 1, the section being taken on the line 6—6 of Figure 1, 75 in direction of arrow 6, and

Figure 7 is a detail sectional view, the section being taken on line 7—7 of Figure 6.

Referring now to these drawings, the ink is delivered from the ink distributing mechanism to a distributing member shown in the form of a roll or cylinder 1 from which it is transferred to the form member of a printing couple (not shown) in any suitable or desired way, this mechanism not having been illustrated as unnecessary for an understanding of the invention.

The inking mechanism includes a frame or bar termed an ink rail 2 which extends across the machine. Ink is delivered to this rail through a plurality of conduits 3, one of these conduits being provided for each column or for desired sections of the form or forms on the form member of the printing couple. In the particular construction shown for illustrative purposes, there are thirty-two of

these conduits for supplying ink to four-page wide plates, each page being eight columns wide. Ink is delivered to these conduits under pressure by means of a plurality of pressure devices, not shown, such as the pumps of the White patents above referred to, these pumps being located in a fountain or reservoir indicated generally by the numeral 4.

Ink is delivered from the conduits to ink delivery openings or nozzles 5, one of these nozzles being provided for each conduit and being formed in the ink rail before referred to. In accordance with the invention, these conduits do not deliver directly to the distributing member of the couple, as in prior practice, but deliver to a distributing member which is so constructed and arranged that it may be readily and quickly removed and replaced with another distributing member having a different number of ink distributing openings or nozzles and from which the ink is delivered to the distributor.

While the specific construction and arrangement of this member may be widely varied, in the particular construction illustrated this distributing member is in the form of a plate or bar, and preferably this bar is centrally divided, as indicated at 6 in Figure 2, the two parts of this bar being marked 7 and 8. This bar is secured in position on the rail by screws 9 and is held in position in any suitable way.

In the particular construction shown, the top of the rail 2 is undercut, as indicated at 10 in Figure 1, and the bottom of the bar is formed with beveled portions 11 cooperating with the undercut portion 10 of the rail so that the bar is securely held in position but may be readily taken out by simply removing the screws 9 and sliding the two parts of the bar endwise of the rail.

This bar is provided with the required number of distributing nozzles or openings, thirty-two being shown in the present instance corresponding to the thirty-two columns or sections of a four-page wide paper having eight columns to the page, these nozzles being marked 12 and delivering to the ink distributing member 1 before referred to. Communication to the nozzles 12 in the bar and the nozzles 5 in the rail is provided by means of ports 13 formed in a central web 14 of the bar, one of these ports being provided for each of the nozzles 12.

In the best constructions the discharge nozzle or openings of the ink distributing member are formed so as to break up the stream of ink flowing therefrom so as to afford a smooth, even distribution of the ink from each of the nozzles. In the particular construction illustrated (see Figure 3) the ink bar 7-8 is formed with partitions 15 which separate the nozzles from each other, and between the partitions are provided projections 16 which form channels 17 through which the ink flows to the distributor 1.

Cooperating with the ink distributing bar 60 is a cap or cover plate 18, this cover plate, when in closed position, resting on the partitions 15 and the projections 16, as shown in Figure 1, so that the link is properly directed through the nozzles. This cover plate 18 is secured to the rail 2 so that it may be readily

moved to afford access to the nozzles for cleaning or other purposes and, as shown, it is hinged to the rail by a hinge 19 and is held in closed position by springs 20, which bear against the projections 21.

While the ink distributing member is shown as formed in a bar which is separate from the rail and the cover, it will be understood that under some circumstances, if desired, the ink distributing member having the distributing ports 12 might be formed in the cover 18 and the invention is, therefore, not to be restricted to this separate bar.

The ink rail and the parts associated therewith may be supported in any suitable side frames 22, and the conduits 3 may be conveniently supported in a recess 23 formed in the rail.

In use, if it is desired to change the ink distribution for a form having seven columns, for instance, instead of one having eight, the parts of the removable ink distributing member are removed from the machine and a member having a different number of discharge openings or nozzles substituted therefor, which, as will be understood from the foregoing, can be readily and quickly accomplished.

While the invention has been shown and described in its preferred form, it will be understood that the removable ink distributing member may vary from the specific construction and arrangement of that shown, and the invention is therefore not to be restricted to the construction, arrangement and position of the ink distributing member shown and described, this latter having been selected as embodying the invention in a preferred form.

What is claimed is:

1. In an inking mechanism for printing machines, feeding conduits through which ink is fed for different columns or sections of the matter to be printed, an ink rail, and an ink distributing member supported on top of the rail and having distributing openings for each column or section of the matter to be printed to which ink is delivered from the conduits and arranged to be readily removable to permit its replacement by another ink distributing member.

2. In an inking mechanism for printing machines, feeding conduits through which ink is fed for different columns or sections of the matter to be printed, an ink distributing bar having distributing openings for each column or section of the matter to be printed to which ink is delivered from the conduits and arranged to be readily removable to permit its replacement by another bar and a swinging cap or cover over the bar.

3. In an inking mechanism for printing machines, an ink rail, feeding conduits through which ink is fed to the rail, an ink distributing member to which ink is fed from the conduits having ink distributing open-

ings for each column or section of the matter to be printed removably secured to the rail, and a cover for the openings.

4. In an inking mechanism for printing machines, an ink rail, feeding conduits through which ink is fed to the rail, and an ink distributing bar supported by the rail so as to have a sidewise sliding movement in and out of the machine and having ink distributing openings for each column or section of the form.

5. In an inking mechanism for printing machines, an ink rail, feeding conduits through which ink is fed to the rail, an ink distributing bar slidingly mounted on the rail and having ink distributing openings for each column or section of the form, and a cover over the bar.

6. In an inking mechanism for printing machines, an ink rail, feeding conduits through which ink is fed to the rail, an ink distributing bar having ink distributing openings for each column or section of the form, and a cooperating tongue and groove on the rail and bar for supporting the bar on the rail so that the bar has a sidewise sliding movement in and out of the machine.

7. In an inking mechanism for printing machines, an ink rail, feeding conduits through which the ink is fed to the rail, an ink distributing bar mounted to have a sidewise sliding movement on the rail and having ink distributing openings for each column or section of the form, and a pivoted cover over the bar.

8. In an inking mechanism for printing

machines, an ink rail, feeding conduits through which the ink is fed to the rail, and an ink distributing bar mounted to have a sliding movement on the rail and secured on top of the rail at each end and having ink distributing openings for each column or section of the form.

9. In an inking mechanism for printing machines, an ink rail, feeding conduits through which the ink is fed to the rail, and a two part ink distributing bar supported on the rail each part of which bar has a sidewise sliding movement on the rail in and out of the machine and having ink distributing openings for each column or section of the form.

10. In an inking mechanism for printing machines, an ink rail, feeding conduits through which the ink is fed to the rail, a two part ink distributing bar secured on the rail, each part of which bar has a sidewise sliding movement on the rail, and having ink distributing openings for each column or section of the form, and a cover over the bar.

11. In an inking mechanism for printing machines an ink rail having a flat top, feeding conduits through which ink is fed to the rail, guides formed in the top, an ink distributing bar engaging the guides and slideable sidewise of the top, and having ink distributing openings for each column or section of the form.

In testimony whereof, I have hereunto set my hand.

JOHN J. HALLIWELL.
